UNITED STATES PATENT OFFICE

AUGUST MEYERHANS, OF BADEN, SWITZERLAND

TRANSFORMER

Application filed November 5, 1932, Serial No. 404,911, and in Germany November 30, 1932.

This invention relates to improvements in transformers and, particularly, to transformers required to operate under conditions of heavy load and of variable voltage.

5 Electric locomotives require a transformer structure to receive the trolley line voltage and to supply voltage to the driving motors of the locomotives. The most usual and, certainly, the most efficient operation of 10 driving motors for electric locomotives requires wide voltage variations. Taps on the secondary winding of a transformer are impractical because of the excessive current strength involved and taps on the primary 15 winding of a transformer, by the addition of a sufficient number of turns and the taps necessary to obtain the proper wide range of regulation are also impracticable because of the increased amount of space required therefore. The usual solution of this problem, accordingly, is to provide an auto-transformer 20 between the trolley line and the supply transformer for the motors of the locomotive.

25 This arrangement is, however, not advantageous because of the combined expense and weight of the auto-transformer and the supply transformer and the large amount of space required for properly arranging the 30 same. The weight and space requirements are especially difficult to meet in locomotive construction, for the reason that it is usually desirable to maintain the weight of the locomotive below a certain maximum and because 35 the space available for the arrangement of apparatus within the locomotive structure limits is insufficient.

It is, accordingly, among the objects of the 40 present invention to provide a unitary transformer structure capable of a wide range of regulation for use in such circumstances as require a heavy load with a variable voltage between wide limits.

Another object of the present invention is 45 to provide a single transformer structure which will be lighter and smaller than the auto-transformer and supply transformer combination heretofore used for electric locomotives.

50 Objects and advantages, other than those

above set forth, will be apparent from the following description and the drawing which diagrammatically illustrates an embodiment of the present invention.

Referring more particularly to the drawing by characters of reference, 1 represents a 3-legged core having auto-transformer winding 4 arranged on one of the legs thereof; a primary winding 2 and a secondary winding 3 arranged on another (middle) leg of the core 55 1, leaving one leg of the core unwound. The winding 4 is connected with the winding 2 in conductive, as well as inductive relation. The winding 4 is connected with the trolley line (not shown) and is provided with a plurality of taps to form an auto-transformer connection to winding 2. The operation of the combined structure is such, therefore, that the connection of the supply current to the winding 4 produces, by means of the taps, and 60 the conductive relation between windings 2 and 4, a variable voltage in the winding 3 (which is closely coupled with winding 2). The connections are so made that the voltage supply to the secondary winding 3 may 65 be regulated within wide limits for the purpose of permitting production of the proper starting and operating conditions of voltage and current in the secondary winding 3 which is connected with the electric motors of an 70 electric locomotive. Although not strictly necessary, it is desirable that the core 1 have an unwound leg to form a path for the magnetic flux set up in the core legs occupied by the auto-transformer winding 4 and the flux 75 caused by windings 2 and 3. The unwound core leg accordingly forms a path for a magnetic flux which is the difference of the fluxes in the wound core legs. It is, therefore, 80 advantageous to so regulate the number of turns of the several windings that the flux in the unwound leg is at a minimum.

The arrangement of all of the windings on a single core has the advantages that only a 85 single core is required, which core is utilized to its maximum so that the weight of a separate core for the auto-transformer is entirely eliminated, the expense of the combination is decreased by the cost of such core. Another advantage of the present structure is 90 95 100

that the core loss in the structure is less than the sum of the core losses would be if separate cores were provided for both an auto-transformer and a supply transformer. The 5 structure, according to the present invention, therefore produces the same result that might be produced by the use of an auto-transformer and the usual separate supply transformer with a saving in weight of one core and the 10 corresponding saving in space required for the two structures rather than for the unitary structure, according to the present invention.

15 Although but a single embodiment of this invention has been illustrated and described, it will be understood that various other embodiments are possible, and that various changes may be made without departing from the spirit of the invention or the scope of the 20 appended claims.

The invention claimed is:

1. A transformer comprising a core having a central member and end members extending from one end of the central member 25 to the other end thereof, an auto-transformer winding associated with said end members, and double wound primary and secondary windings on the central member, the primary winding having a common line terminal connection with the auto-transformer winding at one end, and a variable tap connection therewith at the other end, whereby the said primary winding may be energized under full line potential or under a graduated series of 30 steps of less than full line potential.

2. A transformer comprising a closed magnetic circuit member, double wound primary and secondary windings on one part of said member and an auto-transformer winding provided with line terminals on another part thereof, one end of the said primary winding having a common line connection with a terminal of the auto-transformer, and the other 40 end of the said primary winding having a variable tap connection along the winding of the auto-transformer, whereby the said primary winding may be energized by full line potential or by a graduated series of steps of less than full line potential.

50 3. A transformer comprising a unitary magnetic circuit, an auto-transformer winding provided with line terminals on one part of said magnetic circuit, and multiple circuit transformer windings on another part thereof, one of the said multiple circuit windings having one end connected to a line terminal and the other end connectible to variable voltage taps of said auto-transformer winding, 55 whereby the said multiple circuit transformer winding may be energized at full line potential, or any desired lower potential.

In testimony whereof I have hereunto subscribed my name this 18th day of October, A. D. 1929.

65 AUGUST MEYERHANS.
